UNITED STATES PATENT OFFICE.

FOREST CHENEY, OF CHICAGO, ILLINOIS, ASSIGNOR TO CHENEY TALKING MACHINE COMPANY, OF CHICAGO, ILLINOIS, A CORPORATION OF ILLINOIS.

SOUND BOX.

1,402,052.

Specification of Letters Patent. Patented Jan. 3, 1922.

Application filed April 20, 1918. Serial No. 229,697.

To all whom it may concern:

Be it known that I, FOREST CHENEY, a citizen of the United States, residing at Chicago, in the county of Cook and State of Illinois, have invented certain new and useful Improvements in a Sound Box, of which the following is a specification.

My invention relates to sound boxes for disc record talking machines and particularly to a sound box casing having an enlarged air chamber therein.

One of the objects of my invention is to increase the air chamber space within a sound box casing without increasing the size of the casing.

Another object is to provide a means for mounting the diaphragm in the sound box whereby the air space behind the diaphragm is enlarged.

20 A further object is to provide means for retaining a diaphragm in position in a sound box casing while increasing the volume within the air chamber of the casing.

To accomplish the objects of my invention I provide a sound box wherein the open interior portions are of substantially the same diameter from front to back with the provision of a shoulder which projects into the air space a comparatively short distance, 25 in fact about $\frac{1}{2}$ of an inch. The shoulder forms a diminished diameter within the rear portion of the casing which diameter is diminished only $\frac{1}{16}$ of an inch therefore, so that for all purposes of sound reproduction, 30 the diameter of the air chamber within the casing is substantially uniform.

The above recited objects will be apparent from the drawings, wherein—

Figure 1 is a side elevation of a sound box 40 embodying my invention.

Figure 2 is an end elevation thereof looking at the diaphragm end of the casing; and

Figure 3 is an enlarged vertical sectional view on the line 3—3 of Figure 2.

45 The sound box casing is designated by the numeral 5 and has the usual hollow interior portion for the reception of the diaphragm 9, which diaphragm when in position forms an air chamber there behind. In the preferred embodiment of my invention I have shown the hollow interior portion as being substantially uniform in diameter from front to rear; however, the rear portion is slightly smaller than the front portion, the 50 two portions being defined by a shoulder 7 which I have found need be no greater than $\frac{1}{2}$ of an inch, hence for all intents and purposes the interior portion of the sound box may be said to be substantially of uniform diameter throughout. To securely mount 60 the diaphragm against the shoulder 4 which need only be $\frac{1}{2}$ of an inch deep is one of the objects of my invention. I accomplish this by providing a metallic ring or washer 6 adapted to have engagement with its 65 shoulder 7 at the periphery with the greater portion of the ring extending into the open interior of the casing 5, the width of the ring 6 being no greater than necessary to serve as a proper support for the inner dia- 70 phragm gasket 8. The ring is preferably made to oppose any tendency to be pushed out of engaging position with the shoulder 7 by the diaphragm when the latter is inserted in position.

Having formed the casing 5 with the hollow interior portion of substantially the same diameter, the formation of which results in the shoulder 7, I may then mount the ring 6 on the shoulder 7 and then place 75 on the ring a gasket 8, the width of which gasket is not greater than the width of the ring 6. Preferably the portion of the gasket which engages the diaphragm is semi-circular in section to afford substantial line 80 contact with the diaphragm, which line of engagement between the diaphragm and the supporting gaskets and washers is inwardly of the line of engagement between the ring 6 and the shoulder 7. It may here be noted 85 that the diameter of the inner circle of the ring is less than the diameter of the sound box at the inner edge of the shoulder 7 and that the diameter of the outer circle of the ring is but very slightly more than 90 the diameter of the sound box at the inner edge of the shoulder. Then on the gasket 8 is placed the diaphragm 9 and over the diaphragm another gasket 10 similar in section to the gasket 8. The gasket 10 also preferably has substantial line contact with the diaphragm. Then over gasket 10 is placed the retaining ring 11 mounted in a shoul- 95 dered recess 12 in the outer portion of the casing 5. Screws 13 fasten the retaining ring 11 securely in position. It will be observed that by this means of mounting I am able to retain the diaphragm securely in position so as to be acted upon by the usual arm 14 connected through suitable means 100 105 110 115 120 125 130 135 140 145 150 155 160 165 170 175 180 185 190 195 198

- to the needle (not shown). It will be observed that the space within the casing 5 behind the ring 6 is in diameter substantially equal to the outer portion of the interior of the casing. By providing a shoulder of slight width and mounting the inner gasket 8 on a metallic ring, it is possible to do away with the shoulder usually employed to mount such a ring thereby permitting increase in the diameter in the air chamber. This increase tends to amplify and clarify the sound and to transmit it from the diaphragm 9 through the tone arm to the horn.
- 15 Such modifications as are susceptible to a device of this sort, and which come within the scope of the appended claims, I consider as coming within the spirit of my invention.
- 20 I claim:—
1. A sound box mounting for a diaphragm including in combination with a hollow casing, a diaphragm adapted to be connected at its periphery, a washer adapted to bear against the diaphragm at its rear side, said washer having a flat surface, a ring adapted for engagement with the flat surface of the washer, the width of the ring being no greater than the width of said flat sur-
- face, said washer adapted to have a bearing 30 throughout the extent of said ring surface, said ring engaging the shoulder of the sound box only at the periphery of the ring, the surface engagement between the ring and the shoulder being less than the surface engagement between the washer and the ring, the parts being so arranged that the diameter of the inner circle of the ring is less than the diameter of the sound box at the inner edge of the shoulder.
2. A sound box including a diaphragm, said sound box having an air chamber therein of substantially the same bore throughout its depth and provided with a shoulder of slight width, a mounting for securing the diaphragm of said sound box including a ring adapted to engage said shoulder at the periphery of the ring only, the engagement between the ring and the shoulder being substantially less than half of the width of the ring, a washer having a flat surface, which surface engages the ring and which washer supports the diaphragm thereon, and means for fastening the diaphragm in position on said washer.

Signed at Chicago, State of Illinois, this 17th day of April, A. D., 1918.

FOREST CHENEY.
